(57) **CLAIM**

The ornamental design for a combination stand and charger unit including protective cover, as shown and described.

DESCRIPTION

FIG. 1 is a perspective view of a combination stand and charger unit including protective cover from above, showing my new design;

FIG. 2 is a top plan view of the appliance thereof;

FIG. 3 is a front view of the appliance thereof;

FIG. 4 is a rear view of the appliance thereof;

FIG. 5 is a bottom plan view of the appliance thereof; and,

FIG. 6 is a side view of the appliance thereof.

The broken line showing is for illustrative purposes only and forms no part of the claimed design.
